UNITED STATES PATENT OFFICE.

JOHN DONAHUE, OF KNOXVILLE, TENNESSEE.

COFFIN.

SPECIFICATION forming part of Letters Patent No. 763,092, dated June 21, 1904.

Application filed November 27, 1903. Serial No. 182,793. (No model.)

To all whom it may concern:

Be it known that I, JOHN DONAHUE, a citizen of the United States, residing at Knoxville, in the county of Knox and State of Tennessee, have invented a new and useful Improvement in Coffins, of which the following is a specification, reference being had to the accompanying drawings.

My improvement relates particularly to coffins constructed in part of wood and in part of sheet metal, the ends of the coffin being formed of sheet metal and the intervening portion being formed of wood.

The object of the invention is to produce a construction which may be economically manufactured and which shall combine lightness and strength.

In the accompanying drawings, Figure 1 is a side elevation of a coffin embodying my improvement. Fig. 2 is a plan of one end of the coffin, the lid having been removed. Fig. 3 is a horizontal section on the line 3 3 of Fig. 1. Fig. 4 is a vertical section on the line 4 4 of Fig. 2. Fig. 5 is a vertical section on the line 5 5 of Fig. 2.

Referring to said drawings, 1 is the wooden bottom of the coffin, and 2 are wooden side walls joined by their lower edges to the lateral edges of the bottom in the usual manner. 30 End walls 3, each formed by pressing a single piece of sheet metal, are applied to the ends of the side walls 2 and the bottom 1, the latter extending beyond the side walls to conform to and meet the lower edges of the end walls.

The side walls 2 may be provided with suitable wooden moldings, as 4, extending lengthwise along the lower edge of said wall, and 5, extending along the outside of the upper edge 40 of the wall 2 and forming a rest for the lid 6. Said wall may also have a molding 7 intervening between the moldings 4 and 5.

Each end wall is a single piece of sheet metal, and it overlaps the adjacent ends of the wooden walls 2 by extending over the outside of the latter far enough to permit securing thereto in any suitable manner, as by nails 8. If so desired, the outer face of each side wall may be cut away along the portion overlapped by 50 the end wall to a depth equaling the thickness

of said end wall, to the end that the outer face of each side wall and the outer face of the end wall may be flush with each other.

The lower edge of each end wall is preferably fluted, so as to present a mold 9, corresponding to the mold 4 on the side wall 2, the extreme edge of said end wall being turned horizontally, so as to rest beneath the bottom 1 and form a support for the latter, as clearly shown in Fig. 5, and said end wall is also 55 preferably fluted to form a mold 10, corresponding to the mold 7 on the side wall, the mold 9 overlapping the wooden mold 4 and the mold 10 overlapping the wooden mold 7.

The upper edge of the end wall is bent outward horizontally to form a flange 11, standing at an elevation a short distance (approximately one-half an inch) below the upper edge of the side walls. The molding 5 is extended from the side walls around the exterior of 70 the upper portion of the end wall and provided on its inner face with a horizontal saw-cut at proper elevation and of proper depth to receive the flange 11 of the end wall. Said mold and said end wall are joined to each other in any suitable manner, as by gluing or with suitable nails 13. This construction gives the coffin a pleasing appearance and makes the upper portion of each end of the 75 coffin strong and firm and at the same time provides a proper seat for the lid and also provides a wooden face 14 above the flange 11 on the interior of the coffin for the attachment of the upper edge of a fabric lining 15.

The exterior of the coffin may be painted or covered with any suitable fabric.

I claim as my invention—

1. In a coffin, the combination with the bottom, 1, and wooden side walls, 2, of sheet-metal end walls of less height than the side walls and suitably secured to said bottom and having their vertical edges overlapping the exterior of said side walls and having their upper edge bent outward to form a horizontal flange, and an exterior wooden molding 90 surrounding the upper portion of said side walls and said end walls and having a saw-cut receiving said flange, substantially as described.

2. In a coffin, the combination with the bot-

100

tom, 1, and wooden side walls, 2, of sheet-metal end walls having their vertical edges overlapping the exterior of said side walls and having their lower edge suitably secured to said bottom, and a molding, 5, extending along and suitably secured to the exterior upper edge only of said side walls and said end walls, substantially as described.

In testimony whereof I have signed my name, in presence of two witnesses, this 18th ¹⁰ day of November, in the year 1903:

JOHN DONAHUE.
